UNITED STATES PATENT OFFICE.

CHARLES H. MILES, OF FORT WORTH, TEXAS, ASSIGNOR TO MOTOR EQUIPMENT COMPANY, OF FORT WORTH, TEXAS, A FIRM COMPOSED OF O. S. LATTIMORE, SR., K. D. HOLLAND, R. C. LEWIS, AND C. H. MILES.

PISTON-PACKING.

1,205,558.

Specification of Letters Patent. Patented Nov. 21, 1916.

Application filed October 2, 1913. Serial No. 792,988.

To all whom it may concern:

Be it known that I, CHARLES H. MILES, a citizen of the United States, residing at Fort Worth, in the county of Tarrant and State of Texas, have invented certain new and useful Improvements in Piston-Packing, of which the following is a specification.

My invention relates to piston packing for steam or internal combustion engine pistons, and the object is to provide perfect packing expansible rings for plunger pistons so that there can be no leaking of steam or of explosive force past the pistons and to provide a continuous packing surface both in the bottom of the groove of the piston and on the exterior surface of the packing.

Other objects and advantages will be fully explained in the following description and the invention will be more particularly pointed out in the claims.

Reference is had to the accompanying drawings which form a part of this application.

Figure 1 is a top plan view of the packing rings. Fig. 2 is an inverted plan view. Fig. 3 is a similar view to Fig. 2, but showing how the rings may be cut away as much as one third and still be perfect packing rings. Fig. 4 is a cross-section of the packing rings fitted in a piston groove.

Similar characters of reference are used to indicate the same parts throughout the several views.

The improved packing is made up of a spring open ring 1 which has a right angle flange 5 at the top, and an exterior open ring 2. The ring 1 is open at 3 and the ring 2 is open at 4. The flange 5 is an exterior flange and extends outwardly flush with the outer surface of the ring 2. A lug 6 may be attached to the exterior of the ring 1 at the point 4 where the outer ring 2 is severed to prevent circumferential movement of the ring 2 on the ring 1. The joint between the flanged ring 1 and ring 2 is a ground joint and no gas or other element will pass through this joint. For this reason, gases or any other element cannot pass below the bottom edges 7 of the rings, where one ring is cut away the other being continuous and the two rings having their bottom surfaces 7 flush with each other. There is thus a continuous packing surface in the bottom of the groove in the piston. The ground

joint 8 will be steam or explosive mixture 55 tight. The packing surface will be continuous on the outer periphery because of the ground joint 8 and because that part 9 of the flange 5 will bridge the cut-out 4 between the ends of the ring or packing 2. 60 The pressure of the explosive force in internal combustion engines will be on the edge 10 of the packing and will thus press the two edges 7 against the bottom of the groove in the piston. As above pointed out, 65 the two edges 7 make a continuous packing surface in the bottom of the groove, consequently the packing will be gas and steam tight against pressure on the top edge 10 of the packing.

Attention is called to the fact that the greater packing surface of the packing shown is parallel with the surface of the piston and the less packing surface is perpendicular or at right angles to the surface 75 of the piston. The two members of the packing being made of spring metal, the tendency will be to expand and to keep the piston packed.

In Fig. 4 12 indicates the pressure end of 80 a piston. The piston has an annular groove therein and the packing side of the groove in pistons for internal combustion engines is indicated at 11. The edges 7 of the packing members will press on the side 11 and 85 form a perfect seal. The packing member 2 and the flange 5 will make a continuous pressure surface for sealing against the interior of the cylinder.

What I claim is,—

1. Piston packing comprising an inner open ring member having a flange at the top edge projecting radially outward and providing a packing or pressure surface on top thereof and an open ring member mounted on the exterior of said inner member and having the outer surface thereof flush with the outer surface of said flange and having the bottom edge thereof flush with the bottom edge of said inner member, both members being automatically expansible by the resiliency of the metal.

2. Piston packing comprising an inner open ring automatically expansible member provided with an exterior flange projecting 105 radially from the pressure edge thereof forming a pressure surface on the top edge of the ring and an outer open ring auto-

matically expansible member mounted on the exterior of the said inner member and having its peripheral pressure surface flush with the outer edge of said flange and having its bottom edge flush with the bottom edge of said inner member and said members being connected by a ground joint.

In testimony whereof, I set my hand, in the presence of two witnesses, this 29th day of September, 1913.

CHAS. H. MILES.
